UNITED STATES PATENT OFFICE.

BYRON M. GUNSTON, OF OSWEGO, NEW YORK.

HEMMER FOR SEWING-MACHINES.

SPECIFICATION forming part of Letters Patent No. 351,762, dated November 2, 1886

Application filed March 6, 1886. Serial No. 194,259. (Model.)

To all whom it may concern:

Be it known that I, BYRON M. GUNSTON, a citizen of the United States, residing at Oswego, in the county of Oswego, State of New York, have invented certain new and useful Improvements in Sewing-Machine Hemmers, of which the following is a specification, reference being had therein to the accompanying drawings.

10 Figure 1 is a diagram, showing the shape of the slotted blank before it is bent in proper shape to form the adjustable part of my improved hemmer. Fig. 2 is a top view of this adjustable part properly bent. Fig. 3 is a front edge view of Fig. 2. Fig. 4 is a perspective view showing the improved hemmer applied to a scroll-bearing extension of a foot of a sewing-machine. Fig. 5 is a perspective view of the foot, its extension, and scroll, without the adjustable portion represented by Figs. 1, 2, and 3. Fig. 6 is a vertical section through Fig. 4 in the plane indicated by the dotted lines, Fig. 4. Fig. 7 is a perspective view showing a modification of my device. 25 Fig. 8 is a plan view of the scroll D and foot extension B, having the portion A, Fig. 6, cut off. Fig. 9 is a bottom view of the presser-foot and scroll, and Fig. 10 represents the scroll in blank form before it is bent into shape. 30 This invention relates to improvements in sewing-machine hemmers; and my object is to construct a hemmer in a novel manner, which is adjustable for different widths of hems, as will be fully understood from the following description when taken in connection with the annexed drawings.

Referring to the accompanying drawings, A designates the presser-foot for a sewing-machine, and a the vertical aperture through 40 which the needle plays. At the toe of this foot is a transverse guiding ridge or rib, b, and from this toe projects a depressed angular portion, B, terminated by a narrow rib, b', between which latter and the broad rib b is a transverse 45 groove, b², for a purpose hereinafter explained, the floor of which is perforated vertically, and such perforations screw-tapped to receive a binding-screw, C, (shown in Figs. 4 and 7.)

D designates the tapered scroll for turning 50 the inner edge or fold of the hem. This scroll is secured to the oblique or beveled edge of

the slotted extension or angular portion B by brazing, soldering, or in any other suitable manner, so that the top of said portion and scroll are near a level. This scroll consists of 55 a bottom portion, c, a top portion, c', and an intermediate tapered tongue, c², at the left-hand side of which is a notch, c³. The right-hand side of this scroll presents the longitudinal spaces—that is to say, the edges of the portions are disconnected. The right-hand corner, c⁴, of the top portion, c', is turned up so as to prevent the cloth from catching at this point.

I will now describe my improved adjustable 65 portion E of the hemmer, shown finished and attached to the angular foot-extension in Fig. 4. This portion E, like the scroll D, is formed out of a thin metal plate, and consists of a bottom portion, d, a top part, d', having parallel 70 slots d² d³ through it, and bars d² d³ d⁴, the middle one, d³, of which is marked off to form a gage or rule by which the hemmer can be adjusted for different widths of hems.

Between the bottom and top portions is a 75 narrow tongue, d⁵, which is about equal in width to the width of the front bar, d², and lies directly beneath it and has its free end turned down, as shown in Fig. 3 at e. This tongue d⁵ serves to hold up the top fold of the 80 cloth on its way to the scroll D and to keep the cloth smooth and even, and the short curve e somewhat stiffens this tongue.

In addition to the parts of the cloth-guide E, above described, there is a part, d⁶, which 85 is directly above and parallel to the bottom portion, d, upon which part d⁷ the extension B and scroll rest.

By reference to Fig. 4 it will be seen that the two rear bars, d² d³, lie in the grooved portion 90 of the foot-extension or angular portion B, and are guided by the two ribs b b' thereon, that the binding-screw C is used to rigidly secure the adjustable cloth-guide E to said angular portion, and that the upturned corner or lip 95 c⁴ of the scroll D rises through the slot d⁵, so that it will not interfere with the passage or feeding of the cloth. It will also be seen that by simply loosening the binding-screw C the device E can be adjusted endwise, either to 100 the right or left, and set by the rule-marks on the bar d³, above described, for turning any de-

sired width of hem, limited only by the length of the device E.

It will be further observed that the tongue d' , being made narrow, will not interfere with the application of the extension or angular portion B and its scroll D, and that the operator can view the front end of the scroll through the slot d' .

By reference to Fig. 8 it will be seen that I employ that portion which I have denominated the "extension B," independently of the pressure-foot A. In this modification I make said extension and its scroll precisely as above described, but do not attach it to the foot, which latter may be made in the usual well-known manner. Instead of using the foot as a support for the hemmers I employ a bent-plate, G, the portion g of which is slotted to receive a binding-screw, that secures it fast upon the bed-plate of the sewing-machine. The narrow raised tongue g' is perforated and adapted to be received on top of the adjustable portion E of the hemmer, between the two ribs $b b'$ of the angular portion B. The single binding-screw C thus serves to secure the portion B and the hemmer E to the overhanging tongue g' of the plate or bracket G, and by loosening the screw which passes through the slotted portion g of the plate G the operator can sew as near to the edge of the hem as desired.

By loosening the binding-screw C the cloth-guide E can be adjusted toward the right or left hand for different widths of hems. It will thus be observed that my improvement may be applied directly to a pressure-foot or to a separate support adjustably secured upon the bed-plate of a sewing-machine.

Having described my invention, what I claim, and desire to secure by Letters Patent,

40 is—

1. The combination, with the angular portion B, having upturned ribs and a perforation, of a scroll or turner for the inner edge of the hem, having a tongue portion between its upper and lower tapered portion, and an upturned corner, c' , said scroll being rigidly secured to the beveled edge of the portion B, substantially as described.

2. The combination of the angular ribbed and perforated portion B, and its scroll D, having an upturned corner, c' , free open spaces on its right-hand side, and a notch, c'' , at its lower left-hand corner, the cloth-guide E, having rule-marks on one of its bars, a binding-screw, and a support on a sewing-machine for said devices, substantially as described.

3. The combination of the angular portion B, formed with ribs $b b'$, the scroll portion D, constructed as described, with the upturned corner c' , the slotted adjustable cloth-guide, e , also constructed as described, and the binding-screw C, substantially as specified.

4. The cloth-guide E, formed of a single piece, and consisting of the bottom portion, d , a top part, d' , slotted as described, a part, d'' , directly above the bottom portion, d , and a narrow tongue, d''' , curved at e , in combination with the ribbed angular portion B, having the scroll secured to it, and formed as described, and the binding-screw C, all constructed and adapted to operate substantially as specified.

In testimony whereof I affix my signature in presence of two witnesses.

BYRON M. GUNSTON.
